ATTORNEYS

UNITED STATES PATENT OFFICE.

JESSE BOWEN, OF LANCASTER, OHIO.

BED-BOTTOM.

SPECIFICATION forming part of Letters Patent No. 226,026, dated March 30, 1880.

Application filed September 9, 1879.

To all whom it may concern:

Be it known that I, JESSE BOWEN, of Lancaster, in the county of Fairfield, and in the State of Ohio, have invented certain new and useful Im-
5 provements in Bed-Bottoms; and I do hereby declare that the following is a full, clear, and exact description thereof, reference being had to the accompanying drawings, and to the letters of reference marked thereon, making a
10 part of this specification.

The nature of my invention relates to bed-bottoms; and it consists in the construction and arrangement of devices, as will be herein-after more fully set forth.

15 In the annexed drawings, Figure 1 is a plan view, and Fig. 2 a longitudinal vertical section, of my invention. Fig. 3 is a detailed view of a part thereof.

A represents a bedstead, provided near each 20 end with a cross-bar, B, which has a narrow rib, *a*, on top, extending the entire length. Upon these the bed-slats C C are laid, and held from any lateral movement by means of upward-projecting pins *b* passing through slots
25 *x* in the slats. The ends of the slats C are passed under other cross-bars, D, at the ends of the bedstead.

Each slat C has on its under side two bridges, 30 *I I*, as shown, and near each end of the slat is, by a staple, *e*, or its equivalent, connected a rod, *d*, which extends inward to the lower end

of the corresponding bridge I. At this point the rod *d* connects with a double hook, *h*, around which is placed a spiral spring, *i*. Another double hook, *h'*, is also passed in op- 35 posite direction through the spring *i*, and the two double hooks *h' h'* are connected by a rod, *f*, thus forming a spring-connection between the extremities of the slat under the bridges.

It will readily be seen that the heavier the 40 person is the more resistance the springs will give, and take-up nuts or similar devices are provided for regulating the tension of the springs.

Having thus fully described my invention, 45 what I claim as new, and desire to secure by Letters Patent, is—

In a bed-bottom, a series of slats having their ends placed over cross-bars B, and held down by cross-bars D, and each slat provided 50 with bridges I, rods *d*, double hooks *h h'*, springs *i*, central connecting-rod, *f*, and devices for regulating the tension of the springs, substantially as and for the purposes herein set forth. 55

In testimony that I claim the foregoing I have hereunto set my hand this 16th day of August, 1879.

JESSE BOWEN.
